UNITED STATES PATENT OFFICE

RALPH YUTTS, OF MIAMI, FLORIDA

DUSTER AND HANDLE

Application filed October 29, 1931. Serial No. 571,928.

This invention relates to certain new and useful improvements in dusters and handles and more particularly to the type of duster illustrated in the patent to Ralph Yutts, Number 1,836,103, and divisional application filed Oct. 29, 1931, Serial Number 571,927.

The primary object of this invention is to provide a novel form of duster and handle wherein the duster embodies a handle shank portion and a flaring frusto-conical dusting portion with a tubular handle member enclosing the handle shank portion of the duster and of a length to facilitate gripping of the duster for use and for confining the handle shank portion of the duster in pleated, crimped or bunched formation.

With the above and other objects in view that will become apparent as the nature of the invention is better understood, the same consists in the novel form, combination and arrangement of parts hereinafter more fully described, shown in the accompanying drawing and claimed.

In the drawing:—

Figure 1 is a plan view of a strip of material employed in the manufacture of the duster illustrating one side edge thereof as pleated and the other side edge slitted at acute angles to said edge to provide wisps with a portion of the sheet collapsed or moved into closely pleated formation;

Figure 2 is a plan view, similar to Figure 1 wherein the sheet or strip material is of a crinkled character having one side edge angularly cut as in Figure 1 and further showing a portion of the strip or blank crimped or bunched to form the handle shank and duster portion;

Figure 3 is a developed perspective view of the roll handle showing the gummed strip at one side edge thereof for retaining the flat form in rolled formation;

Figure 4 is a perspective view of the handle in rolled formation and so retained by the gummed strip;

Figure 5 is a side elevational view of the bunched duster pleated as in Figure 1 with the tubular handle shown in section; and

Figure 6 is a side elevational view of the crimped duster shown in Figure 2 and bunched with the tubular handle shown in section.

The material employed in the manufacture of the duster may be of any appropriate character, such as paper, fabric or the like and for purposes of clearness, the material will hereinafter be referred to as paper and the same may be plain, crepe, crinkled or in other forms suitable for the special purposes ascribed thereto. The tubular handle of the duster may also be formed of any appropriate material such as fabric, paper or cardboard and may be of a suitable thickness or comprised of plies to add sufficient rigidity for the manipulation of the duster.

As shown in Figure 1, the duster is formed of a sheet or elongated strip of paper having one longitudinal edge thereof creased to provide pleats that extend transversely of the sheet a suitable distance to form the handle shank portion of the duster while the other side edge of the sheet is slitted at acute angles to the longitudinal edge of the sheet as at 11 to provide bristles or wisps 12.

The sheet or strip illustrated in Figure 2 possesses a crimped or crinkled characteristic along one side edge thereof as at 13, extending transversely of the strip a distance sufficient to form the handle shank, while the opposite side edge of the sheet or strip is angularly slitted as at 11' to provide bristles or wisps 12', similar to the slits and wisps shown in Figure 1.

In bunching the pleated side edge of the strip shown in Figure 1, the pleats 10 are moved into relatively close relationship as indicated at 10' and this bunching of the pleated edge may be accomplished in a manner to produce a substantially cylindrical handle shank portion 14 as shown in Figure 5, while the bunching of the crinkled side edge 13 of the form of strip illustrated in Figure 2 results in the formation of a substantially cylindrical handle shank portion 15 as shown in Figures 2 and 6. During these operations, the diagonally cut wisp portions 12 and 12' are moved into outwardly flaring substantially frusto-conical duster forma-

tions 16 and 17 respectively as illustrated in Figures 5 and 6.

To retain the bunched duster constructions in duster formation as shown in Figures 5 and 6, a tubular handle retainer is provided, the same being formed from a blank 18, such as is shown in Figure 3 having a gummed strip 19 attached to one side edge thereof and extending beyond said edge as at 20. The completed handle formation is illustrated in Figure 4 as being of tubular form, the blank 18 being rolled with opposite side edges thereof overlapped with the extension edge 20 of the gummed strip 19 being adhesively secured to the adjacent portion of the handle blank 18'. The handle may be attached to the handle shank of the duster during the formation of the latter as by rolling the blank 18 into handle formation 18' with the gummed strip edge 20 retaining the same in such form, or said handle blank 18 may be preformed as illustrated at 18' in Figure 4 and thereafter applied to the handle shank portion of the duster. Also, if desired, the tubular handle 18' may be introduced into a socket portion of the handle or the handle 18' may be used alone.

While there is herein shown and described the preferred embodiment of the invention, it is nevertheless to be understood that minor changes may be made therein without departing from the spirit and scope of the invention as claimed.

I claim:—

- 35 1. The combination with a duster having a flared duster portion and a cylindrical handle shank portion, of a tubular handle on the cylindrical handle shank portion including a rolled sheet carrying a projecting gummed strip at one side edge for retaining the handle in tubular formation on the cylindrical handle shank portion.
- 40 2. The combination with a duster having a flared duster portion and a cylindrical handle shank portion formed by the bunching of the material at one end of the duster, of means for retaining the bunched end of the duster in handle shank formation and providing a stiffened handle therefor including a sheet of material rolled into overlapping relation to provide a cylindrical casing around the bunched end of the duster and being of stiffer material than the duster, said rolled sheet being adhesively retained in cylindrical casing formation providing a reinforced stiffened handle inclosing the handle shank portion of the duster.

In testimony whereof I affix my signature.
RALPH YUTTS.
